UNITED STATES PATENT OFFICE.

JACOB F. DERKSEN, OF CHINOOK, MONTANA.

END-GATE.

1,326,482.

Specification of Letters Patent. Patented Dec. 30, 1919.

Application filed May 7, 1919. Serial No. 295,308.

To all whom it may concern:

Be it known that I, JACOB F. DERKSEN, citizen of the United States, residing at Chinook, in the county of Blaine and State 5 of Montana, have invented certain new and useful Improvements in End-Gates, of which the following is a specification.

This invention relates to an improved end gate for wagons or the like and has as its 10 primary object to provide an arrangement wherein accidental release of the end gate will be prevented.

The invention has as a further object to provide an improved catch for automatically 15 locking the end gate when moved to closed position.

And the invention has as a still further 20 object to provide an end gate catch which may be readily applied to end gates already in use without necessitating material change therein.

Other and incidental objects will appear hereinafter. In the drawings:

Figure 1 is a perspective view showing 25 my improved end gate in closed position within a wagon body, the wagon body being conventionally illustrated,

Fig. 2 is a fragmentary longitudinal sectional view bringing out the manner in 30 which the improved catch of the end gate is adapted to lock the end gate closed and

Fig. 3 is a fragmentary vertical sectional view more particularly illustrating the 35 mounting of the catch.

In carrying the invention into effect my improved end gate is formed of swingingly connected sections 10 and 11 respectively, adapted to fit between the sides of a wagon 40 body in the manner suggested in Fig. 1 of the drawings. Fixed at one end to the inner end of the section 11 is a locking arm 12 which, when the end gate is closed, overlaps the joint between said sections seating 45 flat against the outer face of the section 10. The arm 12 is tapered somewhat toward its free end and at its outer portion is formed with a medial longitudinally extending slot 14. At its lower edge, the outer 50 terminal of the arm is cut away as shown at 16.

Mounted upon the outer end of the arm 12 is a catch designed to automatically lock the end gate closed. This catch includes a 55 housing which, as best shown in Figs. 1 and 2, forms a continuation of the tapered outer

end portion of the arm. The housing is preferably constructed of sheet metal and comprises a rear side plate 17 provided adjacent its inner end with lateral flanges 18 60 seating against the upper and lower edges of the tapered outer end of the arm and screwed or otherwise secured thereto. In this connection, it will be observed that the lowermost of the flanges 18 terminates at 65 the cut away portion 16 of the arm. Closing the housing at its outer end is a curved end plate 19 which, at its upper end, abuts the uppermost of the flanges 18 while the lower end of said plate terminates in spaced relation to the lowermost of said flanges, defining 70 a finger receiving opening 20 at the lower edge of the housing. The end plate is provided with curved side flanges, the innermost of which is riveted or otherwise secured to 75 the rear side plate 17. Closing the housing at its outer side is the front plate 21 of the housing resting at its rear end against the outer flange of the end plate 19 and at its forward end portion against the outer side 80 of the free end of the arm 12, being secured to said arm by spaced screws 22. At its rear end, the front plate carries an arcuate keeper plate 23 which is riveted or otherwise secured to the plate 21 and engages beneath 85 the outermost flange of the end plate for thus rigidly connecting the front plate at its rear end with the end plate. Rigidly connecting the front plate at its forward end with the rear side plate 17 of the housing are 90 tie rods 24. Thus, as will be seen, the outer end portion of the arm 12 is inclosed within the housing and, as particularly brought out in Fig. 3, the slot 14 extends somewhat beyond the inner end of the housing. 95

Extending between the front and rear side plates of the housing are spaced guides 25 and 26 respectively. The guide 25 is, as particularly shown in Fig. 3, arranged at the 100 inner end of the housing and extends through the slot while the guide 26 is arranged to abut the outer end edge of the arm, terminating at its lower edge at the cut away portion 16. At their side margins, these 105 guides are formed with lateral flanges 27, the flanges at the inner side margins of said guides being riveted or otherwise secured to the rear side plate 17 of the housing while the flanges at the outer side margins of the 110 guides receive screws or other suitable fastening devices 28 engaged through the outer

side plate 21 for thus rigidly sustaining the guides. Slidable through the guide 25 is a catch bolt 29 provided with a stem 30 slidably received through the guide 26. Sur- 5 rounding the stem of said bolt is a helical spring 31 bearing at one end against the bolt head and at its opposite end against a suitable washer carried by the stem to abut the guide 26. Detachably connected to the 10 outer end of the stem is a lever 32. This lever is preferably formed from a piece of suitable sheet metal and is channel shaped in cross section, being detachably secured to the stem by a pin or other suitable fastening device 33 extending through the side flanges of the lever. At its lower end, the lever projects into the finger receiving opening 20 and preferably terminates flush with the lower side edges of the front and rear 15 side plates of the housing. In this connection, it will be noted that the front and rear side plates of the housing are, adjacent the opening 20, formed with laterally bulged portions in order that one of the fingers may be inserted in said opening at the cut away portion 16 of the arm 12 and engaged with the lower end of the lever. In order to accommodate the bulged portion on the inner side plate, the section 10 of the end gate is, 20 as shown in dotted lines in Fig. 2, suitably recessed. As will be understood, the spring 31 will normally hold the catch bolt projected and will thus normally clamp the lever 32 against the guide 26, the lever acting 25 to limit the bolt in its outward movement. Mounted upon the section 10 of the end gate to be freely received through the inner end portion of the slot 14, is a keeper 34. This keeper is substantially U-shaped and the sides thereof are provided with lateral flanges riveted or otherwise secured to 30 said end gate section. The connecting portion between the sides of the keeper is, as particularly shown in Fig. 2, inclined inwardly toward the outer end of said section in order that the catch bolt 29 may readily 35 ride thereover.

Assuming the end gate to be closed, as shown in the drawings, it will be seen that 40 the catch bolt 29 is engaged beneath the keeper 34 for securely locking the end gate so closed. Furthermore, since the lever 32 is not exposed, possibility of accidental actuation of this lever for releasing the catch bolt will be reduced to a minimum while 45 the spring 31 will prevent the catch bolt from being jarred or jolted out of engagement with the keeper. Consequently, accidental release of the end gate will be effectu- 50 ally overcome. However, by engaging the lever 32 at its lower end and swinging said lever rearwardly, the lever will fulcrum at its upper end against the guide 26 and retract the catch bolt from engagement with 55 the keeper. The arm 12 may then be read-

ily swung outwardly and the end gate dis- 60 placed from the wagon body. When arranging the end gate in position within the wagon body, it will simply be necessary to properly position the ends of the sections 10 70 and 11 with respect to the cleats upon the sides of the wagon, in the manner well understood, and then swing the arm 12 inwardly when the catch bolt 29 will ride over the keeper 34 and automatically engage 75 therewith for locking the end gate closed.

I accordingly provide a particularly simple and effective construction for the purpose set forth. In this connection, attention is directed to the fact that the catch of the 80 present invention may be readily connected to end gates of the general type herein illustrated by simply forming the gate with a longitudinal slot at its free end portion for receiving the keeper 30 and catch bolt when 85 the housing may then be slipped on over the outer end of the arm and secured in position. Thus, end gates already in use may be readily equipped with my improved catch. In order to gain access to the interior of 90 the housing it will simply be necessary to displace the two tie rods 24 when the screws 22 and 28 may be removed and the outer side plate 17 of the device taken off. However, it will be seen that by employing tie 95 rods to hold the outer side plate at one end and by also employing the keeper plate 23 to hold the outer side plate at its opposite end, accidental release of the plate will be avoided.

Having thus described the invention, what is claimed as new is:

1. The combination with an end gate formed of pivotally connected sections, and a locking arm rigidly connected to one of 105 said sections and provided with a slot, of a catch including a housing carried by the free end of said arm, a spring pressed catch bolt slidable within the housing to be received within said slot, an actuating lever mounted within the housing and coacting with said bolt whereby the bolt may be retracted, and a keeper carried by one of the sections of the end gate and adapted to project through the slot to be engaged by the 110 catch bolt.

2. The combination with an end gate formed of pivotally connected sections, and a locking arm fixed to one of said sections and provided with a slot, of a catch for said 120 arm including a housing fitting over the free end of the arm, a spring pressed catch bolt mounted within the housing and received within said slot, an actuating lever connected with said bolt and lying within the lines of 125 the housing, said lever being operable for retracting the bolt, and a keeper carried by one of the sections of the end gate and adapted to project through the slot to be engaged by the catch bolt.

3. The combination with an end gate formed of pivotally connected sections and having an arm fixed to one of said sections and provided with a slot, of a catch for said arm including a housing fitted over the outer end of the arm, guides within the housing received within said slot, a spring pressed catch bolt slideable upon said guides, an actuating lever connected with the bolt and being adapted when actuated to coact with one of the guides for retracting the bolt, and a keeper carried by one of the sections of the end gate and adapted to project through the slot to be engaged by the catch bolt.
- 10 4. The combination with an end gate formed of pivotally connected sections and having an arm fixed to one of said sections and provided with a slot, of a catch for said arm including a housing fitted over the outer end of the arm, guides within the housing received through said slot, a spring pressed catch bolt slideable upon said guides,
- an actuating lever pivotally connected intermediate of its ends with said bolt and normally abutting one of the guides for holding 25 the bolt against outward displacement, the lever being adapted to fulcrum against said guide for retracting the bolt, and a keeper carried by one of the sections of the end gate and adapted to project through the slot to 30 be engaged by the catch bolt.
5. A catch for end gates including a housing adapted to fit over an end gate locking arm, said housing being formed with side plates having spaced guide members extending therebetween, a spring pressed catch bolt slideable upon the said guide members, and an actuating lever connected intermediate of its ends with said bolt and adapted when actuated to fulcrum against one of said 35 40 members for retracting the bolt.

In testimony whereof I affix my signature.

JACOB F. DERKSEN. [L.S.]
